UNITED STATES PATENT OFFICE.

FRED A. DAWSON, OF INDIANAPOLIS, INDIANA.

FREIGHT CHECK.

Application filed June 3, 1921. Serial No. 474,731.

To all whom it may concern:

Be it known that I, FRED A. DAWSON, a citizen of the United States, residing at Indianapolis, in the county of Marion and 5 State of Indiana, have invented certain new and useful Improvements in Freight Checks, of which the following is a specification.

This invention relates to a method of keeping current record in railway freight houses of the handling of a multiplicity of small package shipments in less than carload lots. In the handling of this class of freight under present methods there are many opportunities for errors which are detected only in rechecking and at a time after the loading of the car or cars has progressed so far as to render necessary corrections not only difficult but incurs much loss of time, labor and expense.

One of the objects of the present invention is to not only eliminate many of the steps of rechecking, etc., but enable the rechecking to be carried forward as the work of loading the cars proceeds, so that if any error occurs 20 its detection and correction is immediately possible, thereby eliminating many of the petty and yet serious annoyances constantly arising in the present rechecking systems in use in freight houses in the handling of the 25 above class of shipments.

In order to understand the present methods employed in the handling of package freight in less than carload lots by the majority of railways; the points and sources 30 where errors most frequently arise and their correction, it is deemed desirable to briefly outline the methods most commonly in use at present, and then describe the applicant's method by which the possibility of errors is 35 practically overcome, and in case of an error how its detection and correction is speedy and certain.

Railway loading platforms at the freight houses are divided into sections known as 40 "blocks" or "spots" which are assigned numbers, generally arranged in numerical order. When an article is received at the unloading platform the drayman presents a bill-of-lading, accompanied by a carbon copy 45 known as a shipping ticket, to the receiving clerk who is familiar with the various blocks and destinations of the shipments which load therein. The receiving clerk enters the proper block number on the shipping ticket, 50 showing the location of the car into which the articles are to be loaded, and he also

gives the shipping ticket an individual identifying number. The shipping ticket in this condition goes to the tallyman who supervises the loading of the cars in the various 55 blocks. As each trucker proceeds with a load the tallyman gives him a plain uncarbonized freight check on which the tallyman transfers, by pencil, the block number, the identifying number of the shipping ticket and 60 also indicates on the freight check the number of pieces on the truck. The trucker takes the freight check with the shipment to the designated block and after placing the shipment in the car deposits the freight 65 check into a drop box suspended on the side of the car. These freight checks are collected at frequent intervals during the day and are taken to a designated office to which the shipping tickets are also sent by the tallyman after the loading is completed. In this 70 office the freight checks are matched with the shipping tickets to ascertain whether the ballot number, the number of pieces in the shipment, and the block number in which 75 the loading was done, agree. During the operation of matching the freight checks and shipping tickets, it is possible to detect transposition of figures designating the block 80 number, number of articles, etc. This 85 matching of the freight checks with the shipping tickets is a tremendous and expensive task, necessitating the employment of many persons for the reason that the number of freight checks and shipping tickets 90 representing the transaction of shipments each day will amount to several thousand. In case any error should be detected during this operation of matching the freight checks with the shipping tickets, its correction 95 requires a large amount of labor for the reason that the loading has progressed to a point where it is difficult to correct without the rehandling of a large number of loaded packages.

The invention will first be hereinafter more particularly described with reference to the accompanying drawings which are to be taken as a part of this specification and later pointed out in the claims at the end of 105 the description.

In said drawings:

Figure 1 is a plan view of a pad of freight checks illustrative of my invention.

Figure 2 is a similar view illustrating data 110 supplied by the tallyman.

Figure 3 is a similar view of a loading doc-

ument or bill of lading illustrating the manner in which the check is used.

With the use of my improved checks, each constituting a single sheet designated by the numeral 10, the possibility of error in handling and accounting for package freight in less than carload lots is materially reduced, and in case of an error being made its immediate detection and correction is possible. This method of handling package freight is accomplished by the use of prescribed checks 10 which, for convenience in handling, may be gathered together in pads, in the manner shown in Fig. 1. The upper and side edges of the checks in each pad are left free, their lower ends being usually secured by any suitable adhesive or mucilaginous material to prevent the checks from becoming accidentally disarranged and lost, but permitting the removal of one or more of the checks from the pads as the work of loading the shipments proceeds. The back of each check 10 is carbonized so that figures and writing impressed on its face by the tallyman are transferred to and made of permanent record on the shipping ticket, waybill or dray ticket, hereinafter referred to as the loading document 11, upon which the check 10 is placed. As an initial step in the elimination of errors and possible loss of packages, the checks are numbered in consecutive order, and the tallyman to whom one or more pads of checks are assigned is charged with the total number of checks and he must return all used and unused checks at the end of the day's work or must give proper account of any unreturned checks. This method immediately affords an opportunity for investigating any unsatisfactory explanation that may be given in lieu of the unreturned checks, and their whereabouts ascertained.

The face of each check 10 is preferably subdivided by means of certain horizontal rulings 12 and 13 for defining a number of major areas, designated by the numerals 15, 16 and 17, and one of these major areas, preferably 15, is further subdivided by the vertical rulings 20 and 21 so as to provide minor areas designated by the numerals 24, 25 and 26, for purposes to be hereinafter more particularly described.

Each tallyman is in charge of two or more truckmen, and a loader or picker. The tallyman calls for the shipment he desires placed upon the truck; and to tabulate the number of pieces placed on the truck of a given shipment the tallyman places one of the checks 10 upon the face of a loading document 11 and copies the original number "7875" of the check in the minor area 24 as it appears in the major area 16 of the check. In the adjacent area 25 he enters the number of pieces on the truck, for instance "3," "5" or "7," etc., and in area 26 he enters the block

number, for instance, "55," which designates the block for locating the car into which the shipment is to be loaded. As check 10 is carbonized on its rear surface the numerals written on its face by the tallyman are transferred to the body of the loading document 11, clearly shown in Fig. 3. After a check is filled in by the tallyman the latter hands it to the truckman who proceeds with the loaded truck to the block number indicated in the minor area 26. After unloading the pieces from the truck into the car the truckman stamps the number of the block on the major area 17 of check 10, this stamp being provided for that purpose and is fastened to the side of the car. The block number so stamped in major area 17 of the check by the truckman should agree with the number of the block inserted by the tallyman in minor area 26, unless the truckman made his delivery in the wrong block. The truckman returns the stamped check to the tallyman so that the latter may verify the correctness of the truckman's loading, by examining the returned check and see whether the block number stamped on the check by the truckman corresponds with the block number he previously entered in minor area 26 of the check. In case the truckman unloaded the freight into a car in the wrong block, the stamp number of that block will appear in major area 17 of check 10 and will not agree with the entry made by the tallyman in minor area 26, whereby the mistake is immediately detected and the pieces changed to the right car before further loading progresses. Moreover, it frequently happens that more than one truck load is necessary to transfer a consignee's shipment from the platform to the car, and as a separate check 10 is given to the truckman for each truck load, the tallyman can also ascertain on the loading document if the total number of pieces transferred thereto by the several checks agrees with the original number of pieces placed on the loading document by the shipper. With the use of the present invention the possibility of partial shipments will also be overcome, together with the annoyances attending mistakes of this character, which mistakes are of common occurrence under the old systems, where such mistakes are detected mostly at the points of destination.

As hereinabove stated, practically all errors are detected and can be corrected at the time the checks are returned by the truckmen to the tallymen, but in case of an error getting passed the tallymen it is easily detected in the Revision Office where the checks may be examined, on complaint of the shipper, to ascertain at what point and by whom such error, if any, was made.

With the use of applicant's freight check the collecting together, arranging and

matching of all checks with the shipping tickets, as obtains under the old system, is dispensed with, thereby eliminating both a tedious and expensive operation, together with the employment of a large operative force necessary in the daily task of examining the data relating to thousands of shipments, for the reason that with the use of applicant's invention the history and progress of each step in the operation of loading a given shipment into a car is indicated on the check, or checks, representing said shipment, said data being transferred to the loading document where all the data is finally brought together with the original entries of the shipper.

Having thus fully described my said invention, what I claim as new and desire to secure by Letters Patent, is—

20 1. A freight check for use with a loading document in loading package freight comprising a sheet having its surface divided into a plurality of major areas, one of said major areas being subdivided into minor areas, one of said major areas bearing the original number of the check, and another appropriately designated to receive the duplicate block number, the minor areas appropriately designated to receive the duplicate 25 check number, the number of pieces constituting a truck load, and the block number, said sheet being provided with a transfer

medium on its back whereby the data added to the face of the sheet is transferred to the loading document when the sheet is superposed on the loading document, substantially as set forth. 35

2. A freight check adapted to be used in conjunction with a loading document for loading package freight in less than car load lots comprising a sheet having its surface divided by horizontal ruled lines to provide a plurality of major areas, one of said major areas being further subdivided into minor areas by vertical ruled lines, one 40 of said major areas provided with the original number of the check, and another appropriately designated to receive the duplicate block number, and the minor areas appropriately designated to receive the duplicate 45 check number, the number of pieces constituting a truck load, and the block number, said sheet being provided with a transfer medium on its back whereby the data added to the face of the sheet is transferred to the loading document when the sheet is superposed on the loading document, substantially as set forth. 50

In witness whereof, I have hereunto set my hand and seal at Indianapolis, Indiana, this 28th day of May, A. D., one thousand nine hundred and twenty-one. 55

FRED A. DAWSON. [L.S.]
